UNITED STATES PATENT OFFICE.

ALBERT KRAUTH, OF HAMILTON, OHIO, ASSIGNOR TO KRAUTH & BENNINGHOFEN, A COPARTNERSHIP COMPOSED OF ALBERT KRAUTH AND CHRISTIAN BENNINGHOFEN, OF HAMILTON, OHIO.

PRINTING-PRESS.

1,132,191.

Specification of Letters Patent. Patented Mar. 16, 1915.

Application filed July 1, 1912. Serial No. 706,975.

To all whom it may concern:

Be it known that I, ALBERT KRAUTH, a citizen of the United States, residing at Hamilton, in the county of Butler and State 5 of Ohio, have invented certain new and useful improvements in Printing-Presses, of which the following is a specification.

My invention relates to improvements in printing presses, with the press of a type primarily adapted for printing autographic register strips of paper in which each signature is numerically indicated and registered and accurately spaced to insure a satisfactory use when a web is mounted within an autographic 10 register and to align with a series of sheets of duplicate subject-matter. Therefore, in this respect, my press comprises embodiments peculiar to the character of the usage of the printed matter. The press is provided with 15 perforating and numbering mechanisms for numbering consecutively each signature and for perforating the same to serve as aligning means in the usage of the printed matter when fed in autographic registers and as 20 the original web is of an area to simultaneously print an original signature and record copies thereof, the web may be severed into continuous strips dividing the various units. It is obvious, however, that the press contains 25 many features adapted for printing presses in general and while the drawings show the press designed for a special use it is readily apparent that the press and features thereof are not limited to such particular use.

One of the objects of my invention is to provide a series of printing mechanisms, comparatively arranged to print upon both sides of the web of paper; primarily on one side 40 and subsequently on the reverse side during the feed of the paper through the machine with the printing in different colors or otherwise as desired.

Another object of my invention relates to 45 means for adjusting the platen cylinders relative to the printing cylinders to regulate the density of the impression and the essential characteristics reside in providing circumferential angular bearing plates upon 50 the ends of the platen and printing cylinders with the angle of one bearing relatively opposed to that of its companion bearing, whereby the lateral adjustment of a platen cylinder enables it to be moved to or from 55 its companion printing cylinder and produc-

ing a micrometer adjustment in a true plane over the entire circumferential area of the cylinder. This is especially advantageous in this type of machine where an electro-type printing plate of circular form is used, as 60 it overcomes all blocking difficulties heretofore resorted to for properly aligning the impression surface of the printing plate relatively with the platen cylinder.

The features of my invention are more 65 fully set forth in the description of the accompanying drawings, forming a part of this specification, in which:—

Figure 1 is a side elevation of my improved printing press illustrating what may 70 be termed the power side of the machine, containing the transmission to the various cylinders and ink distributing rolls. Fig. 2 is a detailed elevation of the paper tension device mounted at one end of the press. 75 Fig. 3 is a side elevation of the press opposite from that of Fig. 1. Fig. 4 is an enlarged detailed section through the punching mechanism taken on line m, m , Fig. 3. Fig. 5 is an elevation of one end of the 80 punching mechanism taken on line x, x , Fig. 1. Fig. 6 is an enlarged detailed section through the punching members at their point of registration. Fig. 7 is a section on line v, v , Fig. 4. Fig. 8 is an enlarged side 85 elevation of two of the printing rolls illustrating more clearly the hand levers for adjusting the printing and platen rolls or cylinders relatively to each other and the means for moving the printing cylinder out of contact with the platen cylinder. Fig. 9 is a section on line w, w , Fig. 8. Fig. 10 is a top plan view of the numbering mechanism taken on line z, z , Fig. 1. Fig. 11 is a section on line y, y , Fig. 10. Fig. 12 is an enlarged detailed plan view of the numbering 90 disks. Fig. 13 is a section on line u, u , Fig. 12. Fig. 14 is a side elevation of a portion of the ink reservoir. Fig. 15 is a section on line n, n , Fig. 14. Fig. 16 is a diagrammatic 95 view illustrating the path of the paper and the relative position of perforating, printing and numbering mechanisms.

In order to get a general understanding of the operation of my printing press, reference is had to Fig. 16. 1 represents a web of paper fed upwardly between the perforating disks 2, 3, advancing and passing between the cylinders 4, 5, of which cylinder 4 is the printing cylinder containing the 100 105 110

printing plate, while cylinder 5 is the platen cylinder, its periphery provided with the usual form of tippet to present a yielding surface common to all printing presses. A 5 represents the ink distributing mechanism for conveying ink from the ink reservoir through the ink spreading rollers to the ink distributing roll engaging the impression surface of the printing cylinder 4. As the 10 paper advances, it passes between the cylinders 6, 7, in this instance arranged above the first set of printing cylinders with the cylinder 6 comprising the printing cylinder, while cylinder 7 comprises the platen cylinder, 15 and is preferably arranged above and parallel to the platen cylinder 5. Thus the first set of printing rolls or cylinders print on one side of the paper, while the second set will print on the reverse side. The second set of printing cylinders may print in 20 a different color from that of the first set as independent ink distributing mechanism is provided for each set of printing cylinders. B represents the inking mechanism of the 25 second set of printing rolls or cylinders 6, 7. From the second set of printing rolls the paper passes between a third set of printing rolls, which, for convenience, I term record cylinders, which are primarily used to designate the character of the impression or 30 signature as indicating which signature is the original, duplicate, triplicate, etc., thereof, as manifolding is one of the principal objects in the use of the printed matter. The 35 machine receiving the printed webs, which are usually in the nature of sales sheets or strips, maintains the rolls or webs of paper in a condition to be fed through the register and over manifolding sheets for making 40 record copies of an original transcript. The number of manifold copies being optional to meet the requirements of a particular user. With this third set of printing cylinders the original transcript is usually 45 printed with the numeral 1 in a different colored ink than the main printed matter and directly over the same with the record or manifold transcript printed with a number designating its character. 8 represents 50 the printing cylinder, and 9 the platen cylinder of the third set of rolls and C the ink distributing mechanism for distributing ink to the impression surface of cylinder 8. 55 From the third set of printing cylinders the paper is fed between the numbering mechanism for consecutively numbering each transcript or signature with the means for consecutively adjusting the numbering 60 disks or tumblers arranged to be automatically thrown out of commission after a predetermined number of impressions has been made to permit a given number of signatures to be fed through the numbering 65 mechanism to receive duplicate members, in-

dicating a division between two lengths of paper, each comprising a length sufficient to form a web for use in an autographic register. This is advantageous as the duplicate numbered signature can serve as 70 waste in alining the sheets in an autographic register without destroying the consecutively numbered signatures in reloading the register. After the paper passes the numbering mechanism it is again rewound 75 on a receiving roll from whence it is fed through severing mechanism for dividing the various transcripts and arranging each into the register size of web.

With my improvements in printing 80 presses the capacity is very materially increased and the various elements conveniently adjusted, very materially reducing the time in which the machine is out of commission for changing forms or regulating 85 the density of the impression as the thickness of the tippet on the platen or cylinder can be changed without removing the web of paper or without disturbing the correlative alinement of the printing cylinder 90 with the platen cylinder. The printing cylinder is journaled in eccentric bearings rotatively mounted with means for rotating the eccentrics to swing the printing cylinder to and from the platen cylinder. The platen cylinder at each end thereof is provided with an inclined angular flange adapted to engage with oppositely inclined flange similarly disposed at each end of the printing cylinder to define the limit of the correlative 100 adjustment of the two cylinders toward each other and thereby controlling the density of the impression. The adjustment is made by moving the platen cylinder axially to change the points of engagement of the 105 inclined surfaces of the annular flanges of said rolls. This enables convenient renewal of the tippet surface by increasing or decreasing the thickness thereof which must be renewed as soon as it shows sign of wear 110 and which renewal is more repetitious in highly speeded machines than otherwise. Therefore, it can be readily seen that to maintain a high capacity for printing presses the construction must be such as to 115 reduce to a minimum the time per days run and time out of commission for adjusting, reloading or resetting for a change of run. 15 represents the base of the machine upon which the side frames 16 are mounted. As 120 illustrated in Fig. 1, substantially all of the rotative elements are positively driven, preferably by gear transmission connected in train with the driving shaft of a main driving pulley. This prevents any lost action 125 or slippage of the various rolls or cylinders which would have a tendency to disturb their correlative operation, as the arrangement and type of machine disclosed is designed for a given length of signature al- 130

though the width may be of various area. 17 represents the main driving pulley mounted upon the shaft 18, suitably journaled within bearings formed in the side frames 16, with the driving pulley arranged adjacent to a loose pulley, (not shown) on shaft 18, for throwing the drive into and out of commission by shifting the belt from the driving pulley 17 fixed on the shaft upon the loose pulley or the reverse as desired. The mechanism for shifting the belt, is, for the sake of clearness, omitted from the drawings as any well known form of belt shifting mechanism or clutch mechanism may be provided for throwing the power into and out of commission. The main driving shaft 18 may be provided with a break mechanism actuated simultaneously with and by a lever mechanism controlling the power, and provisions may be made for preventing reverse rotation of the main driving shaft or the rotatiye elements driven thereby which might have a tendency to injure some of the elements. Such devices are common in this class of machine and while pertinent as component parts of the machine as a whole does not form a part of this invention and therefore specific description and illustration thereof is hereby omitted.

30 *Transmission.*—As the various sets of printing instrumentalities are driven by gearing in train with the main driving shafts 18, I will first describe such gearing leading to the various divisions.

35 20 represents a pinion fixed on the shaft 18 in mesh with a gear 21, said gear being fixed to a shaft journaled within bearings formed in the side frames 16. 22 represents a gear in mesh with gear 21 and with a gear 24 which latter gear is in mesh with a gear 23. Gears 22, 23 and 24, forming the members of a train of gearing for driving the rewinding roll of the web at the rear or right hand side of the machine, as illustrated in Fig. 1. The function of the rewinding rolls and their operation to be hereafter more fully described.

25 25 represents a gear in mesh with gear 21 and with a gear 26. The gear 26 is in mesh with a gear 27 for imparting motion or rotation to the numbering mechanism, the said gear 26 is also in mesh with a gear 28 and the latter in mesh with gears 29 and 30, gear 29 conveying motion to the third set of printing cylinders and ink distributing mechanism, while gear 30 conveys motion to a gear 31 with the latter in mesh with gear 32, imparting motion to the second set of printing mechanism. The gear 31 is keyed to the shaft of the impression cylinder 7 from which motion is conveyed to the shaft 105 of the cylinder 5, through intermediate gears 116 and 117 secured to the cylinders 7 and 5 respectively, (see Fig. 9), the pitch diameter of the gears 116 and

117 is greater than that of the gears 31 and 33, thereby relieving the teeth gears 31 and 33 of driving contact with each other. This arrangement permits the spacing of the cylinders 7 and 5 with their surfaces out of contact with each other and at the same time prevents backlash or free play that would be present if the drive was direct from gear 31 to gear 33, said gears having their pitch lines separated on account of the cylinder 75 spacing. The gear 33 is in mesh with a gear 34 conveying motion to the first set of printing mechanism, while gear 35 is in mesh with a gear 36. Gear 36 is in mesh with a gear 37 conveying motion to the perforating 80 mechanism. Thus it will be seen that a single source of power is utilized for transmitting motion to the various divisions providing a positive drive free from slippage or lost motion and by constructing the intermeshing gears of different kinds of metal, as for instance, the one of bronze and second steel, the machine runs practically noiseless, at the same time increasing its life. But as a positive drive is an important desideratum 90 to the successful operation of this type of machine, I have found the arrangement herein illustrated as the most satisfactory and practical. The supply web of paper is rotatively mounted with provision made for applying tension thereto to prevent unfolding of the web greater than its feed and maintaining the web taut at all times in its travel through the press. Means are also provided for laterally adjusting the web to 100 readily position a new roll with the function instrumentalities of the press. The mechanism provided is illustrated in Figs. 1 and 2.

38, 39, represent brackets extending from the main frames 16, providing a bearing for the spindle 40, with the bearings of notched form, providing an opening for the convenient and ready removal of the spindle. As the webs are provided with a hollow 110 core, the spindle is provided with a plug member 41 fixed thereto and driven into the ends of the web core, securely mounting the web in position upon the spindle.

42 represents a pulley fixed to the spindle, 115 preferably at one end thereof, and outside of the right hand frame, said pulley being provided with an annular groove to receive the strap 43. One end of the strap is secured to a bar of the horizontally projected frame 120 44, see Fig. 2, while the other end of the strap 43 is secured to a collar 45 mounted upon a stud shaft 46 supported in the side frame. The collar is loosely mounted upon the stud shaft or bolt and is fixed to a worm 125 wheel 47 likewise loosely mounted on the stud bolt 46 and in mesh with a worm or screw member 48 journaled in a bracket 49 and provided with a hand wheel 50, for rotating the screw and in consequence the 130

worm wheel 47 for increasing or decreasing the frictional resistance upon the periphery of the pulley 42. By this means the tension of the web can be delicately controlled to maintain the proper tautness of the web and insure an accurate spacing of the printed subject-matter which is very essential in the usage of the printed matter. The frame 44 is of bar or skeleton form, provided with a cross plate 50 at its outer extremity.

51 represents a screw journaled in the cross head 50 and bracket extension 39 and provided with a hand wheel 52 for rotating the same. 54 represents an arm having a threaded engagement with the screw 51, its free end yoked and adapted to engage between the collars 53 fixed to the spindle 40. Thus as the hand wheel 52 is rotated, the arm 54 will be fed by the screw 51, correspondingly moving the spindle 40, providing a lateral adjustment of the web. The yoke limbs of the arm 54 are angled in a direction corresponding to the notch in the bearings of the spindle 40 to enable the spindle to be removed in an upward angular direction. The strap 43 at its end connecting with the collar 45 is notched to enable the same to be readily withdrawn from its collar connection releasing the pulley 42. As illustrated, 30 the arm 54 is slidably mounted upon the bars of the frame extension 44, to maintain the same in a proper position relative with the axial line of the spindle 40. This web tension and adjusting means comprise a very simple arrangement, durable and very accurate and is a very important factor in the successful operation of the press. The paper as it is unwound from the web 1 travels upwardly and between the perforating instrumentalities comprising the following elements:

55 *Perforating mechanism.*—61 represents a shaft journaled in bearings formed in the side frame 16, the shaft carrying the gear 45 37 in mesh with the train heretofore described. Upon this shaft are mounted the lower perforating rolls, adapted to register with companion perforating rolls mounted upon a shaft supported parallel above the shaft 61.

62, 63, represent bearing plates mounted upon the side frame 16 and in which the upper shaft 64 is journaled. These bearing plates are removably secured to the side frames and also serve as means for maintaining the journaled bronzes of the shaft 61, in position within the side frame. This enables the perforating mechanism to be readily removed for changing the perforating rolls, for, as illustrated, the rolls have a permanent location and a predetermined lateral position of the various punch elements relative to each other. It is obvious, however, that the perforating rolls could be 60 constructed to be readily adjustable upon

their respective shafts to change their position relative to the travel of the paper to perforate the same at various points within the margin line of the paper.

65, 66, represent gears fixed to the shaft 70 61 in mesh with gears 66, 66, fixed upon the shaft 64, for conveying motion thereto and provide a double set of transmission between shafts 61 and 64 to insure positive results and avoid, as far as possible, flexing or distorting strains of the shafts which might have a tendency to interfere with the accurate registration of the punching element of the perforating rolls. To accurately register and aline the lower perforating rolls 80 with the upper, I provide means for laterally adjusting the shaft 61.

68 represents a sleeve or thimble, see Fig. 4, provided with an annular flange secured to the side frame 16 with the bore of the 85 thimble screw threaded.

67 represents a sleeve loosely mounted upon a stud projection of the shaft 61, which stud formation provides a shoulder against which one end of the sleeve 67 engages, with the opposite end of the sleeve engaging collar 70, for moving the shaft laterally with the movement of the sleeve 67. The sleeve 67 upon its outer periphery is screw threaded engaging with the threads 95 of the thimble 68, whereby the rotation of the sleeve a movement to the right or left is had according to the direction of rotation thereof.

71 represents a hand hold formed integral 100 with the sleeve for rotating the same.

As illustrated in Fig. 4, the gear 37 is loosely mounted on the shaft 61 with friction clutch mechanism provided for clamping the gear to its shaft to control the operation of the perforating rolls. By this means the perforating rolls can be readily thrown into and out of commission.

The preferred form of clutch mechanism, as illustrated, comprises the following elements:—The inner periphery of the gear 37 is provided with an inclined annulus 72, adapted to engage with the inclined periphery of the friction disk 73. This friction disk 73 is keyed and splined upon the 115 shaft 61. 74 represents a screw rod, screw threaded into the end of shaft 61 and provided with an annular flange 75, one side thereof engaging a collar 76, fixed to the hub of the disk 73. 77 represents a hand wheel fixed upon the screw rod 74, with its hub engaging the collar 76. Thus, by rotating the hand wheel 77 the disk 73 can be fed into and out of its locking engagement with friction surface of the gear 37.

To prevent accidental release or rotation of the hand wheel, I provide a lock vise 78, mounted upon the side frame, having jaws adapted to engage the hand wheel for locking said hand wheel against rotation.

The construction of this hand wheel locking mechanism may be of any desired form, but the preferred type herein illustrated, which is utilized to block the various adjusting hand wheels of the machine of which all are the duplicates, will be more clearly described in detail herein.

The perforating rolls herein illustrated are formed in unitary pairs for providing 10 eight perforations in a relative spaced lateral plane, but it is obvious that the number of perforations or relative spacing may be of any number or degree to answer the requirements. But as it is essential to provide 15 a substantial design of construction to prevent distortion or displacement of the coacting elements by an improper registration thereof, rigidity of the elements is an important factor, owing to the wide unsupported area of the shaft between their bearings having a flexing tendency detrimental to obtaining a clear cut perforation. Therefore, wherein possible, I mount the punch elements of a series in unitary roll members 20 25 in preference to individual punch element carrying rolls. As an additional safeguard against roll flexation, I provide the tie bars 79 spanning the perforating rolls and connected to the bracket plates 62, 63. The perforating rolls 2, 3, as illustrated in Fig. 4, are arranged in unitary pairs and arranged to make eight perforations in a lateral plane. The upper rolls 2 are provided with the punch pins 80, each seating within an orifice formed in the periphery of the roll, see 35 Figs. 4, 6 and 7, with the punch pins of sleeve formation with the bore thereof screw threaded to receive the adjusting screws 82, whereby the punching end of the punch pins 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

perenced in perforating instrumentalities of this class and in which the delicacy of the adjustment of the punch pin relatively to and with its coacting die element is microscopically obtained and thus maintained. 70 The continuity of the operation of the press is not disturbed to the degree heretofore experienced under existing methods and obviates what might be termed hand repairing of the die members by the operator for producing clean cut perforations. It would be possible to more elaborately discuss the advantages of my improvement in this capacity, but it is deemed that the foregoing is sufficient for the purposes herein. 80

In the arrangement shown the perforating rolls are the first to act upon the paper in its travel through the machine, but it is obvious that the perforating may be accomplished at any stage and occupies the position as one of convenience for access to the perforating rolls to adjust the punch pins or remove the rolls to change from one unitarily spaced set to that of the second. 85

From the perforating rolls, the paper 90 travels through the printing rolls 4, 5, these rolls are driven and inked and comprise the following instrumentalities:—

Cylinder adjustment.—90 represents a shaft supporting and rotating the printing 95 roll or cylinder 4, see Figs. 8 and 9, mounted in the eccentric bushings 91, journaled within the side frames 16, and upon one end of the shaft 90 there is fixed the gear 34, forming a member of the train heretofore 100 described. The gear 34 is of two part form with one member adjustable upon the other and comprises a hub member 92, which is keyed to the shaft 90, and a rimmed member 93, having its web provided with semi-circular slots 94, through each of which, see Fig. 1, a bolt 95 passes. This enables the shaft and its roll to be adjusted rotatively without disturbing the correlative time function of the rolls and without disturbing the 110 intermesh of the gear.

It is very desirable to have the printing roll move out of engagement with the platen roll for inserting new printing plates or throwing the same out of commission, 115 this being accomplished as follows:—96 represent rack segments fixed to each of the eccentric bushings 91, each having its teeth intermeshed with a rack pinion 97, fixed to the rock shaft 98, supported in the 120 side frame 16 and projected beyond one side thereof. Thus as the rock shaft 98 is rotated it will rotate the gears 97 and their intermeshing rack segments correspondingly rotating the eccentric bushings changing the axial line of shaft 90, and its impression roll correspondingly to and from the platen roll. 99 represents a quadrant fixed to side frame provided with a semi-circular slot 100, through which a lock pin

With my form of punch pins of sleeve formation with an adjusting screw concentric therewith, I am enabled to provide a seat for the punch pins within the rolls with the punch pins engaged against the same at all times, prevent their displacement and overcome many difficulties heretofore ex-

101 projects, forming a locking member for locking the rock shaft 98 in any adjusted position. The lock pin 101 projects through an orifice formed in the handle lever 102 with one end provided with a hand wheel 103 and its opposite end with a nut 104. By rotating the hand wheel the pin and nut can be tightened or released to allow the pin to slide freely in the semi-circular slot 100 and also permit movement of the hand lever. By this means the printing roll can be easily and conveniently moved to and from its companion platen roll for renewing or changing the texture of the tippet wound on the periphery of the platen roll. The printing roll may be provided upon its periphery with axially arranged grooves or T slots to accommodate registering hooks used for securing the impression or electro-type plate. The method of securing the impression or printing plates is not herein illustrated, but as this feature is not a part of my invention, only forming a component part of the machine as a whole, specific illustration or detailed description need not be given further consideration herein. 105 represents a shaft for supporting and rotating the platen roll 5, journaled in bearings formed in the side frames 16. This shaft is provided with the gear 33 which is intermeshed with the gear 34, forming members of the train of gearing heretofore described. To control the density of the impression and to define variable limits of printing roll engagement or approach toward each other, I provide means for laterally adjusting the platen roll and its supporting shaft. 106 represents a thimble fixed to the side frame, see Figs. 8 and 9, and 110 represents a sleeve loosely mounted upon a stud projection formed on the end of shaft 105 to provide a shoulder 111, against which the end of the thimble 106 engages. The opposite end of the thimble engages a nut 112, screw threaded upon the stud projection of shaft 105. 113 represents a circular hand hold formed integral with the thimble or sleeve 106. The sleeve has a screw threaded engagement with the thimble and thereby upon its rotation lateral movements are directed either to right or left as desired. The printing and platen rolls are of sectional form as illustrated, but this relates primarily to a feature of good mechanical design comprising two cylindrical members telescopically engaged and mounted upon the driving shaft. 114 represent disks fixed to the ends of the platen roll each having an inclined periphery of a corresponding angle and in the same plane while the printing roll 4 is provided with similar disks 115 likewise having angular periphery disposed in the same plane as their companion disks 114. The highest elevation of the an-

gle projecting beyond the periphery of the roll upon which they are mounted defining the limits from which a set of rolls may be separated by this adjusting mechanism. Thus it will be seen that the adjusting of the platen roll 5 laterally will change the surface engagement of the two sets of disks, consequently varying the relative spacing of the rolls and the pressure of contact of the printing roll upon the yielding surface of the platen roll, thereby governing the degree of roll or cylinder approach to determine the density of the impression. The disks and their adjustment may also be defined as means for providing variable restraining limits of cylinder approach.

Inking mechanism.—Any well known form of inking mechanism may be employed for distributing the ink from an ink reservoir to the impression roll although a preferred embodiment herein illustrated relates primarily in the means for controlling the film of ink deposited upon the surface of the main ink receiving and distributing roll.

120 represents the frame of one of the ink fountains or reservoirs adjustably mounted upon suitable supports formed in the side frames 16. Within this frame is mounted a distributing roll 121 which is intermittently rotated by mechanism of a pawl and ratchet type common in producing the feed of this type of roll which will hereinafter be more fully described in detail.

122 represents a movable wall of the ink reservoir extending parallel with the ink distributing roll 121 and preferably hingedly supported at each end to the ink reservoir frame 120. This swinging frame or wall is locked in its position by means of the set screws 123 engaging with a lug projection extending from the swinging wall 122 and screw threaded into a downwardly projecting web of the ink reservoir frame 120, see Fig. 15. The swinging wall has an inclined surface forming a spout between it and the ink distributing roll 121 into which the ink is deposited. Upon this inclined surface of the swinging wall a flexible plate 124 is mounted, having one edge thereof directed toward the periphery of the ink distributing roll 121 and the clearance between this plate and periphery of the roll 121 defines the degree of thickness of the ink film. To produce a uniform degree of film over the entire ink receiving surface of the ink roll 121 or to variably regulate the degree of film thickness, I provide a series of conically pointed set screws 125, horizontally projecting through the swinging wall of the ink reservoir, adapted to engage with the ink plate 124. By this means the plate can be delicately adjusted throughout its entire length owing to its flexibility and thereby control the amount of ink deposit upon the ink distributing roll 121. 126 represents an

oscillating ink distributing roll, see Figs. 1 and 3, also Fig. 16, which roll is journaled within yoke arms 127 at each end of the roll, which yoke arms are fixed to the rock shaft 128. The mechanism for locking said shaft will be more fully described hereinafter.

129 represents an ink distributing roll receiving ink from the oscillating ink distributing roll 126, the said oscillating roll 10 moving from roll 121, within the ink reservoir to the receiving roll 129, and this roll 129 is also provided with means for continuously moving the same laterally during its rotation which is common practice in ink 15 distributing mechanism to get a uniform distribution and thorough kneading of the ink. The ink distributing roll 129 is in frictional contact with the distributing roll 130. The roll 130 is a power driven roll receiving 20 its rotation by means of a gear 131 in mesh with a gear 132, with the latter gear in mesh with gear 34 of the train heretofore described.

133 represents an ink distributing roll 25 positioned between the printing roll 4 and ink distributing roll 130 and frictionally engaging said rolls for distributing the ink from the inking roll 130 to the printing roll. This combination of ink distributing rolls 30 is common in the art and comprises a combination producing the most satisfactory results for the class of work for which the press is intended. It being understood, however, that various other types of inking 35 devices may be employed without departing from the features of my invention.

From the first set of printing rolls the paper passes to a second set of printing rolls 6, 7, as heretofore referred to for printing 40 upon the reverse side from that of the first set or printing operation with the instrumentalities employed constructed substantially the same as those described for the first set from whence the paper passes to a 45 third set of printing instrumentalities, which, in this character of press, is utilized for indicating a manifold number and which printing instrumentalities may be substantially the same as those heretofore 50 described for the first set and owing to such duplication of elements further detailed description thereof is hereby omitted. In each instance the power driven ink distributing rolls are rotated by gearing in train with 55 the driving gear mounted on the shaft of the respective printing roll of a given set.

It is further obvious that the printing roll of any one or more of the printing sets may be thrown out of commission if such impression 60 is not desired or required for a given class of work without interfering with the remaining set or sets.

Consecutive numbering mechanism.—From the third set of impression rolls the paper

advances through the numbering instrumentalities for consecutively numbering each impression or signature which, in this instance, is the final operation upon the web, but its position and rank can be changed.

134 represents a shaft journaled in the side frames rotated by gear 135, see Fig. 3, with said gear in mesh with a gear 136, mounted on a shaft 137, the opposite end of said shaft carrying the gear 27 in mesh with the train of gearing heretofore described. 70 The gear 135 is of two part form, the hub member being keyed to the shaft 134, with the rim or toothed member loose upon the shaft. The two members are adapted to be frictionally clamped together thereby providing clutch mechanism for controlling the rotation of shaft 134. This mechanism is substantially the same as that heretofore described for controlling the rotation of one of the shafts of the perforating mechanism, 75 and, therefore, further detailed description is herein omitted. Thus it will be seen that the shaft 134 carrying the numbering heads can be readily thrown out of commission while the machine is in operation or the 80 same can be thrown into commission as desired.

In printing autographic register strips it is desirable to consecutively number each signature for record purposes or other uses. 95 The following mechanism is employed in my machine and comprises a rotatable head adjustably mounted upon the shaft 134, with the head containing a series of numbering disks forming a numbering unit, and, as 100 illustrated, the head is provided with two numbering units to print two numbers upon each rotation of the shaft and head, but it is obvious that any number of units may be employed as the occasion demands, this being governed by the length of each signature and the correlative rotation of the numbering head.

140 represents type disks or wheels which may be of any number desired, and, as 110 illustrated, in Fig. 12, six type wheels are provided to each unit. The first wheel of the unit has a series of pins 141, projecting from one side thereof, adapted to engage with lugs 142 projecting from the arm 143 115 mounted upon the slide rod 144, to rotate the numbering wheel one point at each engagement with a particular pin in consecutive order. This engagement is similar to the tooth intermesh of gears, and thereby provides a very positive and accurate rotation in step form of the type wheels for consecutively bringing a number or character into printing position. The first wheel of the series printing the units, the second the 120 tens, etc., throughout the series, and each wheel is required to make a complete rotation before a successive wheel is rotated.

The type wheels are loosely journaled upon a hub 145, projecting from the head or disk 146.

147 represents a spring-controlled pin 5 pawl mounted within the hub 145, adapted to successively engage into the notches 148 cut into the inner periphery of the type wheel for alining the type wheel in a set position. 149 represents a spring pawl secured 10 within one face of the type wheel with its opposite type wheel engaging end normally maintained flush with the face of the type wheel, and in its rotation it will engage with the cam 150, projecting from the hub of the type head, see Fig. 12, directing the pawl laterally so as to move the same into engagement with a notch of an adjacent type wheel and advancing the same one step upon each rotation of the first type 15 wheel or the number of steps dependent upon the number of cams 150 employed in the circuit of type wheel rotation. Each type wheel is provided upon one side with a similar pawl for shifting its next adjacent 20 type wheel when the opposite pawl of an opposite type wheel coincidentally registers therewith.

In the form shown with the provision of 25 two type wheel units, each wheel is advanced two steps in presenting the type characters from one printing position to a second on each rotation of the shaft, in which one unit would print the odd numbers and the second the even numbers for 30 a consecutive printing upon the strip, but the number of units may be varied as well as the relative rotation between the numbering head and travel of the sheet for accomplishing the consecutive number printing or 35 two or more successive signatures can be printed with the same number by changing the number of lugs 142 projecting from the arm 143. It is also obvious that any number of printing heads may be mounted upon 40 the shaft 134 commensurate with the particular printing job. The arm 143 is frictionally clamped upon the slide rod 144, by slotting its sleeve 151, as illustrated in Fig. 11, and providing the hand screw 152, 45 engaging with the projecting ears opposite the sleeve slot. Thus by shifting the arm to the left, from the illustration Fig. 10, the lugs 142 can be disengaged from the type wheel pins 141, discontinuing the step rotation of the type wheels.

It is desirable at times to automatically 50 discontinue the consecutive numbering for a slight period, this being advantageous in printing autographic register signatures which are of a materially reduced length 55 from the web supplying the printing machine, and thereby allow a few signatures as waste in loading and alining the same within an autographic register, without destroying the consecutively numbered signa-

tures for such register loading purpose. Therefore, to automatically discontinue the consecutive number printing for a predetermined interval without interruption to the signature printing, I provide the following instrumentalities:—154 represents a bevel gear fixed upon the shaft 134, carrying the numbering head, which is in mesh with a beveled gear 155, fixed upon the shaft 156, see Figs. 1 and 10, said shaft being journaled in suitable bearings fixed to the side frame of the machine. 157 represents a worm fixed upon the shaft 156, having its teeth in mesh with a worm wheel 158, rotatable upon a stud shaft mounted within the 80 side frame. The periphery of the worm wheel is provided with an annular groove for receiving a lock bolt for clamping a tripping dog 159, upon the periphery of said worm wheel. The number of teeth 85 serving as a gage in setting the tripping dog or dogs, if more than one is employed, for defining the number of consecutive number printing operations to be had prior to each unconsecutively numbered interval. 90 The tripping dog in its circuitous path engages with the arm of the lever 160, projected in the path of the tripping dog, with the opposite arm of the lever connected with the slide rod 144, thus moving the slide rod 95 to the left and maintaining the same in such position as long as the tripping dog 159 is engaged with the lever 160. This will disengage the lugs or pins 142, upon the arm 143, from the pins projecting from the type 100 wheel. 162 represents a spring engaging a collar 163, fixed to the slide rod 144, for directing the slide rod to the right to reengage the type wheel shifting mechanism. The numbering units in their rotation engage with ink distributing roller mechanism, which is substantially the same type of mechanism as that heretofore described for distributing ink to the main printing rollers and the rotating members of the ink distributing mechanism receive their motion by means of the gears 163, 164, intermeshing with each other, and gear 164 intermeshed with the gear 135, rotating shaft 134 carrying the numbering heads, see Fig. 3. 115

As has been heretofore described, the ink distributing mechanism of each printing unit is provided with a ratchet fed fountain ink distributing roll and a reciprocating roll swinging from the fountain roll to an ink 120 distributing roll of the series to provide an interrupted transfer of ink from the fountain roll to the series of distributing rolls which distribution of ink is common in printing presses, and well known to the art, 125 and, therefore, to provide the intermittent rotation of the fountain roll and the oscillating movement of the distributing roll, I provide the following actuating elements: In this regard it might be added that I pro- 130

vide a main actuating member having tributary elements radiating therefrom and connected with respective oscillating ink distributing rolls and fountain rolls, which provides a relative cooperation of the various ink distributing units of the machine.

166 represents a shaft upon which the gear 26, forming one member of the main driving train, is fixed. The shaft extending 10 across the machine and journaled in bearings formed in both sides of the frame, (see Figs. 1, 5 and 16). Near the opposite end of said shaft 166, a cam wheel 167 is mounted, said cam engaging a roller 168 mounted 15 upon the lever 169, with the lever pivoted to a suitable bracket projection extended from the main frame.

170 represents a tension rod engaging with the rock lever 169, to maintain the roller 168 in peripheral engagement with the cam 167. Upon the rock lever 169 a series of connecting rods are pivotally mounted serving as 20 branches extending toward the various ink distributing roller units.

25 171 represents one of these rods extended toward the inking mechanism A and connected to the rock arm 172, which in turn is fixed to a shaft 128. To this shaft is fixed a pair of yoke arms 127, which support the 30 ink distributing roll 126 for rocking the same from the fountain roll 121 to the ink distributing roll 129. This cam is so designed as to provide a period of engagement of the oscillating ink distributing roll, with 35 each of its coengaging ink rolls, as, for instance on one-half of the revolution of the cam 167, the oscillating roll 126 will be in engagement with the fountain roll 121, and during the remainder half of the rotation of 40 the cam the roll 126 will be in engagement with the ink distributing roll 129. This action is maintained with all of the oscillating rolls of the various ink units of the press, and therefore, special reference in each 45 instance need not be made herein.

173 represents a second branch connecting rod pivotally connected with the rock lever 169, and with the rock lever 174 of bell crank form and pivotally mounted upon the 50 side frame. The bell crank lever 174 has a second connecting rod 175 pivotally connected therewith, with the opposite end of said rod connected to a rock arm 176 for oscillating the ink distributing roll 126^b of the inking mechanism B. This rock arm 55 176 is connected to a rock shaft 128^b and the said shaft is provided with a pair of yoke arms for supporting and journaling the oscillating roll 126^b for moving the same to 60 and from the fountain roll 121^b and the ink distributing roll 129^b of said unit B.

180 represents a rod pivotally connected at one end to one arm of the bell crank lever 174, pivotally connected to a rock arm 181, 65 fixed to a rock shaft 128^c of the ink distrib-

uting mechanism C, said shaft 128^c is provided with a pair of yoke arms 127^c for journaling and supporting the ink distributing roll 126^c and oscillating the same to and from the fountain roll 121^c and ink distributing roll 129^c.

177 represents a third branch connecting rod, one end pivotally connected to the rock lever 169, with its opposite end pivotally connected to a bell crank lever 178.

183 represents a connecting rod pivotally mounted upon an arm of the bell crank lever 178. The opposite end of the connecting rod 183 is pivotally connected to a rock arm 184, for oscillating the ink distributing roll 126^d of the inking mechanism for distributing ink to the numbering disks. The rock arm 184 is connected to a rock shaft 128^d with said shaft provided with a pair of arms for journaling and supporting said ink distributing roll 126^d, the roll moving to and from its fountain roll 121^d and ink distributing roll 129^d.

As illustrated, the connecting arms of the series are each adjustably connected to their respective rock arms to properly gage the movement of the oscillating ink distributing roll and which connection may be of any well known form common in the art.

The fountain rolls of each of the ink distributing mechanisms are intermittently rotated and preferably by ratchet mechanism. This intermittent rotation of fountain roll is likewise common in the art of printing presses. 185 represents an eccentric fixed 95 upon the shaft 166 and 186 represents a pitman engaging with the eccentric 185, with the pitman pivotally connected to a Y-lever 187, suitably pivoted to the side frame. The arms of said Y-lever are each connected to 100 a branch connecting rod for actuating the fountain rolls of the ink distributing mechanisms A, B and C. 188 represents a connecting rod, one end connected to the Y-lever 105 the opposite end to a pawl-carrying arm 189, 110 of the ink distributing unit A, with its pawl engaging with a ratchet wheel fixed to the shaft carrying the fountain roll 121.

190 represents a branch connecting rod, one end pivotally connected with a second 115 arm of the Y-lever 187, with its opposite end pivotally connected to a pawl carrying arm 191 with its pawl engaged with a ratchet wheel fixed to the shaft supporting the fountain roll 121^c of the ink distributing unit C. 120

192 represents a branch connecting rod, one end thereof pivotally connected to the third arm of the Y-lever 187, with its opposite end pivotally connected to the pawl carrying arm 193. The pawl of said arm 125 engaging with the ratchet wheel fixed on the shaft of the fountain roll 121^b of the ink distributing unit B.

As illustrated, the three branch connecting rods have each end adjustably connected 130

with their respective rock levers or arms, to regulate the throw of the ratchet mechanism and consequent length or travel of the fountain roll in its intermittent operation.

5 194 represents a connecting rod, one end thereof pivotally connected to an ear projecting from the pitman 186 with the opposite end of said rod connected to one arm of the bell crank lever 195, pivotally supported upon the side frames.

10 196 represents a second connecting rod connected to a second arm of the bell crank lever 195 and to a pawl carrying arm 197, having its pawl engaging with a ratchet wheel fixed to the shaft carrying the fountain roll 121^a of the numbering wheel inking mechanism.

15 The printing cylinders or rolls of each printing unit, namely printing cylinders 4, 20 6 and 8 are each provided with means for moving the same away from their platen roll, the preferably form of mechanism having been heretofore described, which comprises eccentric bushings supported within 25 the side frames and forming bearings for the shafts of the cylinders with each eccentric bushing having a rack segment engaging with a rack pinion and handle means for rotating the shaft supporting relative rack 30 pinions, together with means for locking the handle in any adjusted position, and it is thought that detailed description in each instance is unnecessary herein. Likewise it may be said that all of the rotating hand 35 wheels controlling clutch mechanism are provided with locking instrumentalities for rigidly locking each respective hand wheel against accidental rotation.

40 The continuous length of paper after it has passed through the printing rolls is re-webbed and wound around a core 200 having its trunnions movable vertically in guide bars fixed to the side frame. The periphery of the web engages intermediately upon the 45 rollers 201, 202 rotated in the same direction by the gears 22, 23. Gear 22 being fixed to the axis of roller 201 while gear 23 is fixed to the axis of roller 202. A weighted roller 204 is journaled in the guide bars 205 50 and vertically movable relatively with the increasing diameter of the web which offers sufficient tension to wind the roll with the desired degree of tautness. The speed and ratio of the gears 22, 23 is proportionate to 55 the feed of the paper relatively with the speed of the printing rollers so as not to offer any pulling strains upon the paper. The web being loosely supported and rotated by friction will slip upon the peripheries of 60 the rollers to prevent excessive pull of the paper as the diameter of the web increases.

As a series of printing units are herein shown and described which are more or less required for the particular kind of printing 65 for which the machine is designed, dupli-

cate elements are contained in the various units, therefore, specific inference in each instance as to details is regarded superfluous herein, but such duplicate elements can be regarded as components in each printing unit.

70 The foregoing description includes and the drawings disclose perforating mechanism, numbering mechanism and other diverse features not herein claimed, which are 75 separable herefrom and classifiable in other divisions and reference to the numbering mechanism, which in a unit machine can be combined herewith, is had in a copending application, filed July 1, 1912, Serial No. 80 706,976, and due reservation thereof is hereby made.

Having described my invention, I claim:—

1. In a printing machine, coacting printing cylinders, each provided with angularly disposed peripheries at the ends of the cylinders projecting beyond the major peripheral plane of each cylinder to define variable degrees of cylinder peripheral approach, means for axially longitudinally adjusting 90 one of said cylinders, and means for laterally adjusting one of said cylinders for changing the degree of relative cylinder approach.

2. In a printing machine, coacting printing cylinders, each provided with circumferential angular bearing plates upon the ends of each cylinder, the bearing plates of one cylinder adapted to engage with respective opposite plates of the second cylinder 100 to define the degree of approach of the printing areas of both of said cylinders, and means for laterally adjusting one set of bearing plates relative to the second, and the second axially longitudinally to the first for 105 regulating the degree of approach of said cylinders.

3. In a printing machine, a pair of printing cylinders of a definite diameter throughout their printing areas, the ends of each 110 cylinder provided with conical circumferential bearing faces with the relative opposing bearing faces arranged conversely to each other, and means for axially adjusting said cylinders relatively longitudinally and diametrically for varying the degree of cylinder approach.

4. In a printing machine, a pair of coacting printing cylinders, each having a plane peripheral area with conversely tapering surfaces at each end engaged with each other, and means for relatively axially adjusting said cylinders, longitudinally and diametrically for varying the degree of approach of said cylinders.

125 5. In a machine of the nature described, a frame provided with bearings, a pair of coacting cylinders and shafts therefor, the shaft ends of one cylinder journaled in confined bearings in said frame and longitudi- 130

- nally translatable therein, the shaft ends of the second cylinder eccentrically journaled in rotatable bearings to radially move the same toward and from the other shaft and 5 annular devices coaxially respectively with said cylinders and rigid with their shafts to provide variable restraining limits of cylinder approach.
6. In a printing machine, a pair of co- 10 acting printing cylinders, having their peripheral printing areas correlative toward each other for a defined density of impression, oppositely disposed bearing surfaces of converse angular planes arranged beyond 15 the peripheral printing areas of the cylinders with said opposing surfaces of said cylinders engaged with each other, means for changing said surface engagement longitudinally with the axial line of the cylinders 20 to vary the degree of approach of the printing areas of said cylinders.
7. In a printing machine, a pair of co- 25 acting printing cylinders, circumferential bearing surfaces formed on said cylinders beyond their peripheral printing areas, the surfaces of one cylinder engaging relative opposing surfaces of the second cylinder, with the relative opposing surfaces conversely inclined and defining the degrees of 30 approach of the printing areas of said printing cylinder, means for shifting said surfaces to vary the degree of cylinder approach.
8. In a machine of the nature described, 35 a frame provided with bearings, a pair of parallel shafts journaled in the frame bearings, one longitudinally translatable and second radially toward the first, coöperating printing cylinders one on each shaft, and 40 devices rigid with each shaft, providing restraining limits for cylinder approach variable through the adjustments of said shafts.
9. In a machine of the nature described, a 45 frame provided with bearings, a pair of parallel shafts journaled in the frame bearings, one longitudinally translatable and second radially toward the first, coöperating printing cylinders one on each shaft, and 50 devices rigid with each shaft, providing restraining limits of cylinder approach variable through the adjustments of said shafts, and means for confining the said shafts in their adjusted positions.
- 55 10. In a machine of the nature described, a frame provided with bearings, a pair of parallel shafts journaled therein, one longitudinally translatable and the second radially transferable toward the first, coacting 60 printing cylinders one for each shaft, and coöperating annular devices rigid on each respective shaft and at each end of said cylinders, providing restraining limits of cylinder approach variable with the adjustment of said shafts.
11. In a printing machine, a pair of co- 65 acting printing cylinders, conversely oppositely disposed conical bearing surfaces formed on each of said rolls in relative engagement to define the degree of approach of cylinder peripheral printing areas, a threaded member rotatably mounted upon the axis of one of said cylinders, a rigid member engaging with said threaded element for adjusting said cylinder and its 70 bearing surfaces in a longitudinal plane with its axis for varying the degree of cylinder approach, and means for locking said thread elements against rotation.
12. In a machine of the nature described, 75 a frame provided with bearings, a pair of parallel shafts journaled therein, one longitudinally translatable and the second radially transferable toward the first, coacting printing cylinders one for each shaft, oppositely disposed annular members having inclined peripheries of corresponding angle at their point of tangency, rotating with their respective shaft and disposed at each end of said cylinders to provide axially equalized 80 restraining limits of cylinder approach variable through the adjustments of said shafts.
13. In a machine of the nature described, 85 a frame, a pair of parallel shafts journaled therein, one longitudinally translatable and the second radially transferable toward the first coacting printing cylinders, one for each shaft, and a coöperating member on 90 said shafts axially movable therewith to provide variable separating limits for said shafts.
14. In a printing machine, a pair of co- 95 acting rolls, means for adjusting one of said rolls longitudinally with its axis for co-ordinate peripheral registration of said rolls, eccentric bearing journaling the second roll having a rack segment formed on each bearing, rotative elements engaging with the rack segments, whereby in the rotation thereof the roll will be moved to and from 100 its companion roll, and means for locking the rotative elements in any adjusted position.
15. In a machine of the nature described, 105 a pair of oppositely disposed side frames, a pair of parallel shafts journaled therein coacting printing cylinders, one for each shaft, means for longitudinally translating one of said shafts, rotatable eccentric bearings in each side frame for journaling one 110 of said shafts and thereby transferable toward its companion shaft, actuator coupling means connecting with said eccentric bearing for simultaneously rotating the same, and annular means on said shafts abuttingly 115 providing restraining limits toward each other.
16. In a printing machine, a frame, a pair 120 of coacting printing cylinders journaled thereon, each cylinder having oppositely 125

- disposed peripheral extensions at each end of a corresponding angle in the same plane at their point of tangency, a sleeve rigidly extending from said frame concentric with the axis of one of the cylinders, and a hand wheel loose upon the axis of said cylinders having a hub extension screw-threaded within said sleeve for moving said cylinder longitudinally.
17. In a printing machine, a frame, a pair of coacting printing cylinders journaled thereon, each cylinder having oppositely disposed peripheral extension at each end of a corresponding angle in the same plane at their point of tangency, a sleeve rigidly extending from said frame concentric with the axis of one of the cylinders, a hand wheel loose upon the axis of said cylinders having a hub extension screw-threaded within said sleeve for moving said cylinder longitudinally, and means for adjusting the axis of the second cylinder toward and from the axis of said longitudinally adjustable cylinder.
18. In a printing machine, a frame, a pair of coacting printing cylinders journaled thereon, each cylinder having oppositely disposed peripheral extensions at each end of a corresponding angle in the same plane at their point of tangency, a sleeve rigidly extending from said frame concentric with the axis of one of the cylinders, a hand wheel loose upon the axis of said cylinders having a hub extension screw-threaded within said sleeve for moving said cylinder longitudinally, and means for adjusting the axis of the second cylinder toward and from the axis of said longitudinally adjustable cylinder.
19. In a printing machine, a frame, a pair of coacting printing cylinders journaled thereon, each cylinder having oppositely disposed peripheral extensions at each end of a corresponding angle in the same plane at their point of tangency, a sleeve rigidly extending from said frame concentric with the axis of one of the cylinders, a hand wheel loose upon the axis of said cylinders having a hub extension screw-threaded within said sleeve for moving said cylinder longitudinally, and means for locking said hand wheel against rotative movement.
20. In a machine of the nature described, a pair of oppositely disposed side frames, a pair of parallel shafts journaled therein coacting printing cylinders, one for each shaft, rotatable eccentric bearings in each side frame for journaling one of said shafts and thereby transferable toward its companion shaft, actuator coupling means connecting with said eccentric bearing for simultaneously rotating the same, annular means on said shafts abuttingly providing restraining limits toward each other, and means for longitudinally translating one of said shafts to vary the restraining limits.
- In testimony whereof, I have hereunto set my hand.

ALBERT KRAUTH.
